UNITED STATES PATENT OFFICE.

MAX J. SCHREINER, OF DAVENPORT, IOWA.

BUTTONING DEVICE.

1,098,532.

Specification of Letters Patent. Patented June 2, 1914.

Application filed September 8, 1913. Serial No. 788,592.

To all whom it may concern:

Be it known that I, MAX J. SCHREINER, a citizen of the United States of America, and resident of Davenport, Scott county, 5 Iowa, have invented a certain new and useful Improvement in Buttoning Devices, of which the following is a specification.

My invention relates to improvements in buttoners and has for its object to provide 10 a device by which certain articles of apparel which are highly starched and provided with buttoning means, more or less inaccessible, such as the modern high collar with the closed front, may be readily and easily 15 buttoned without damage to the collar or button holes.

A further object is the providing of a buttoner, simple in construction, durable and easily operated.

20 I attain these objects by the mechanism illustrated in the accompanying drawing, in which—

Figure 1 is a perspective view of my improved device from the top side thereof. Fig. 25 2 is a similar view from the under side. Fig. 3 is a diagrammatic view of the device and parts to be buttoned, showing the operative relation of the various parts of the device. Fig. 4 shows a style of collar button, particularly adapted for use in connection with 30 my device.

Similar reference characters indicate similar parts throughout the several views.

The device consists of the arms or members 35 1 and 2 pivotally connected at 3 and provided with the finger grips 4, similar to an ordinary pair of scissors. In arm 1, near the end opposite from the finger hold, is the notch or indent 5 for engagement with the 40 shank of a collar button. Pendant from arm 2, near the end opposite from the finger hold, is the post 6 provided with the cupped end 7. Hinged to the under side of arm 2 is the stripper 8, notched or bifurcated at 45 its free end to receive the post 6. Journalled in the opening 9 in arm 2 is the cam shaped or bell crank lever 10, normally in contact with the upper surface of the stripper 8. Arm 1 is offset just beyond its pivotal connection with arm 2, a distance somewhat greater than the length of post 6, so that when a button is engaged by the notch 5 with the button head resting on the upper face of arm 1 and the arms are brought into 50 alinement, the button head is forced with

considerable snap into the cupped end 7 of the post 6.

Referring to Fig. 3, A represents a collar button passing through the shirt bands BB, C is the right hand collar tab, 1 is the arm 60 of the device engaging the button shank. 6 is the post of arm 2 passing through the left hand collar tab D. 8 are the stripper prongs.

To be used in connection with the buttoning of a collar, the device would be operated as follows: With the collar buttoned to the shirt band at the back of the neck in the usual manner, the device is secured to the collar by passing post 6 through the button hole in the left hand tab thereof. The right hand tab is then buttoned to the collar button which has been inserted in the shirt bands at the front of the neck. Arm 1 of the device is then connected to the shank of the collar button, on top of or outside of the shirt-bands by hooking same into notch 5. Arms 1 and 2 are then brought into alinement just as are the blades of a pair of scissors. The cupped end 7 of the post 6 is snapped over the collar button head. Lever 10 is then pushed forward forcing the prongs of stripper 8 together with the left hand collar tab along post 6 and over the head of the button. To insure the exposure of sufficient shank surface under the collar button head to receive the left hand tab when it is stripped off of post 6 and over the head of the button A, the shank is recessed where it is to be engaged by the notch 5, as clearly shown at 12 in Fig. 4.

Having described the invention, what I claim as new is—

1. In a device of the class described, the combination of arms pivotally connected for scissor-like movement, a button holding indent formed in the end of one of said arms, a garment holding post and a stripping device connected to the end of the other arm.

2. In a device of the class described, the combination of a pair of arms mounted for scissor-like movement on a common axis, a notch formed in the side of and near one end of one arm, a post having a cupped end secured to the other arm, and a stripper 105 swingingly mounted on said last mentioned arm.

3. In a device of the class described, the combination of a pair of arms the ends of which are capable of movement into and out 110

of alinement with each other, button hooking means formed in the end of one arm, a post secured near the end of the other arm and at a right angle to the face thereof, a stripper pivotally secured to said last mentioned arm and arranged to sweep said post from end to end.

4. In a device of the class described, the combination of a pair of arms connected at 10 about their center of length for scissor-like movement, a notch formed in the side of and near one end of one arm, a post secured near

the end of the other arm and at a right angle to the face thereof, a bell crank lever pivotally mounted on said last mentioned arm, a stripper hinged to said arm provided with an opening at its free end having longitudinally sliding engagement with said post.

Signed by me at Davenport, Iowa, this 5th day of September, 1913.

MAX J. SCHREINER.
